UNITED STATES PATENT OFFICE.

JAMES A. JACOBSEN, OF BUFFALO, NEW YORK.

FEEDING MECHANISM FOR STITCHING MACHINES.

Application filed June 30, 1925. Serial No. 40,640.

This invention relates to a feeding mechanism for wire stitching machines whereby the pamphlets, books or similar articles are automatically fed forwardly one step at a time for the purpose of properly presenting the article to the stitching mechanism and permitting the latter to apply wire stitches in uniformly spaced places thereto.

It is the object of this invention to provide a feeding mechanism of this character which will automatically start the wire stitcher and only perform its stitching operations when a book, pamphlet or similar article is in position to receive stitches, and when no further books, pamphlets or other articles are presented to the stitching mechanism the operation of the latter will be automatically arrested. With this end in view this machine consists generally of means which is adapted to be actuated by the forward movement of the book, pamphlet or the like as different parts of the same are presented to the stitching mechanism and which is operatively associated with the clutch of the stitching mechanism so as to cause the stitch forming and applying mechanism to perform the operation of stitching or stapling the leaves or section of a booklet or pamphlet together at the working place; also to so organize this mechanism that during the stitching operation the stop or trip mechanism which is engaged by the forward edge of the book blank will be lifted out of the path of the latter and then again lowered so as to leave the parts in the proper position for automatically operating the stitching mechanism and applying the next stitch in the properly spaced relation on the book blank without, however, interfering with the forward feed of the latter; and also to combine this automatic feeding mechanism with the parts of the stitching machine proper but when the machine is once started the same will continue in operation so long as books, pamphlets or the like are fed to the same but will automatically cease to operate when such feeding is discontinued.

In the accompanying drawings:—

Figure 1 is a conventional front elevation of a wire stitching or stapling machine equipped with my improved automatic feeding mechanism.

Figure 2 is a side elevation of the same.

Figure 3 is a top plan view thereof.

Figure 4 is a fragmentary front eleva-

tion, partly in section of the machine showing the parts in a position different from that indicated in Fig. 1.

Figure 5 is a similar view showing the parts in still another position.

Figure 6 is a vertical section taken on line 6—6, Fig. 1 showing the book on the saddle-shaped feed table and between the upper and lower rolls or wheels of the feeding mechanism.

Figure 7 is a vertical section taken on line 7—7, of Fig. 1.

Figure 8 is a horizontal section taken on line 8—8, Fig. 5.

This automatic feeding mechanism is applicable to various kinds of wire stitching and stapling machines and the one shown in the drawings is, therefore, to be taken merely as a conventional form which is typical of one suitable for use in connection with this invention. As there shown the same consists essentially of a main frame 10 provided with a lower, forwardly projecting arm 11 and an upper forwardly projecting arm 12, a horizontal and longitudinally extending feed table 13 mounted upon the front end of the lower arm and in this instance constructed in the form of a saddle which is substantially A-shape in cross section, a staple forming mechanism mounted on the front end of the arm 12 and represented generally by the numeral 14, a staple clinching mechanism 15 arranged at the summit of the table 13 immediately below the staple forming mechanism 14 and supported upon the arm 11, a main driving shaft 16 for the machine in the upper part of the main frame, a continuously rotating driving pulley 17 which receives its power from any suitable source, a clutch 18 adapted to connect and disconnect the driving pulley 17 with the driving shaft 16, a manually operated treadle 19 pivoted on the lower part of the main frame and connected by means of a rod 20 with the clutch controlling mechanism 21 at the upper end thereof so that upon depressing the lever 19 the clutch will be coupled and the stitcher will be operated while upon raising this lever this clutch will be uncoupled and the stitching will stop, and a spring 22 for yieldingly holding the clutch operating lever 19 in its elevated inoperative position.

The operator places an A-shaped blank 23, 110 such as a booklet, pamphlet or similar article astride of the front end of the feed table or

saddle 13 and pushes the same forwardly into operative relation to the means which automatically propel this blank into the proper position between the staple forming and clinching mechanism preparatory to applying wire stitches or staples thereto. This feeding mechanism is arranged to operate upon the blanks immediately in advance of the wire staple former and clincher 14 and 10 15 and in the preferred construction shown in the drawings, this feeding mechanism is constructed as follows:—

The numerals 24, 24, represent two lower conical feed rolls or wheels which turn about 15 a horizontal transverse axis relative to the saddle and each of which projects with the upper part of its periphery through an opening 25 in one of the wings of the saddle-shaped table so that the uppermost part of 20 the periphery of this wheel is in line with or slightly above the surface of this part of the saddle. The angle of the conical face of each of these lower feed rolls is preferably the same as the angle of the respective side or 25 wing of the feed table and in its periphery each of these lower feed rollers is provided with an annular groove 26. These two feed rollers are mounted on a transverse shaft 27 which is journaled at its opposite ends in 30 suitable bearings 28 on the adjacent part of the table or saddle and is turned so that the upper sides of the lower feed rollers move forwardly or toward the stitching mechanism. The driving means for this purpose, 35 shown in the drawings, as an example, consists of a lower driven shaft 29 journaled in bearings 30 on the main frame, an upper driving shaft 31 journaled in bearings 32, 33 on the main frame, a belt 34 passing around 40 pulleys 35, 36 secured respectively to the main driving pulley 17 on the shaft 31, a belt 37 passing around pulleys 38 and 39 secured respectively to the shafts 31 and 29, and a belt 40 passing around pulleys 41, 42 secured respectively to the shafts 29 and 27. 45 Above each of the openings 25 is arranged an upper feed roller wheel 43 which has its axis arranged transversely and parallel with the upper side of the respective wing of the feed table and has its lower part arranged opposite with the upper part of the groove 26 in the companion lower feed roller and slightly below the peripheral portions of this lower roller on opposite sides of the groove 50 thereof, so that when a book blank 23 is passed between each pair of these rollers a slight deflection will be produced in this book blank by reason of the three point contact of the upper and lower pair of rollers therewith, as shown in Fig. 6, whereby these rolls 55 obtain a firm grip on the blank and insure a positive forward feed of the same over the table or saddle and pass the stitching mechanism which forms and applies the wire staple or stitches thereto. Each of the up-

per feeding rolls or wheels is turned so that its lower face moves toward the stitching mechanism and advances the booklet in that direction. For this purpose these upper feed rolls are mounted and driven by means which in their preferred form are constructed as follows:—

The numeral 45 represents a depending bracket mounted on the front end of the upper frame arm 12 and provided at its lower 75 part with bearings 46, 47 in two downwardly diverging roller shafts 48, 49 which carry the rollers 43 at their lower ends. These upper rollers are caused to rotate in unison by intermeshing bevel gears 50, 51 secured to the 80 upper ends of their shafts 48, 49, as best shown in Fig. 2. Motion is transmitted to the gears 50, 51 from the upper driving shaft 31 by an intermediate shaft having upper and lower sections 52, 53 which are arranged 85 at an angle relatively to each other and operatively connected by means of a universal coupling 44, the upper shaft section 52 being journaled in a bearing 54 and the lower shaft section 53 in a bearing 55, a pair of 90 co-operating spiral gears 56, 57 secured respectively to the shaft 31 and the upper intermediate shaft section 52 and a beveled gear wheel 58 secured to the lower intermediate shaft section 53 and meshing with 95 the beveled gear wheel 51. The driving mechanism of the upper and lower rolls is so timed that the peripheral speed of these feed rolls is the same thereby avoiding dragging on the pamphlets which are being 100 stitched and insuring proper feeding of the same lengthwise over the saddle past the stitching mechanism.

By constructing each of the lower feed rolls in conical form that part of the peripheral gripping face of each of the lower feed rolls having larger diameter will travel somewhat faster than that part of the conical face of each of these rolls which has a smaller diameter, thereby causing these lower feed rolls to produce a downward drawing effect upon the two wings or leaves of each blank on opposite sides of the summit of the saddle, whereby the blank is drawn tightly downwardly against the saddle and the proper placing of the stitch or staple on the same is assured for the purpose of producing uniform and high grade work.

The driving mechanism which operates the feed rollers operates continuously so long as the machine is in use but the stitching mechanism only operates when a booklet, pamphlet or other blank is in position between the staple forming and clinching mechanism after the machine has been 120 started to effect its first stitching operation, and the blank has been successively advanced step by step for bringing different parts of the blank in spaced relation to the stitching mechanism, but after the feeding of the 125

blanks to the stitching mechanism has been discontinued the operation of the machine will be automatically arrested.

The preferred form of the means whereby this is accomplished is constructed as follows:—

The numeral 59 represents a vertically movable shipper rod which is guided on the main frame and adapted to engage its lower end with the top of the starting treadle 19 for the purpose of tripping the clutch 18 and starting the machine. This trip rod 59 is yieldingly held in its elevated position by means of a spring 60 interposed between a suitable shoulder on the main frame and a collar 61 on the shipper rod 59, as best shown in Fig. 2. The numeral 62 represents a rotary disk which is mounted loosely on the shaft 31 in rear of the stitching mechanism and provided on its periphery with a trip cam 63 which upon engaging a roller 9 at the upper end of the trip rod 59 will depress the latter and start the operation of the stitching machine. Adjacent to the front side of the trip wheel or disk 62 a ratchet driving wheel 64 is secured to the continuously rotating shaft 31 so as to turn in unison therewith. On the front side of the trip disk 62 is mounted a coupling dog or pawl 65, the nose 66 of which is adapted to engage with one or another of the teeth of the ratchet wheel 64 and thereby couple the trip disk 62 with the driving shaft 31. The dog 65 is yieldingly held in a position in which it engages its nose or beak 66 with this ratchet wheel by means of a spring 67 interposed between a shoulder 68 on the trip disk 62 and a tail 69 on the dog 65, as shown in Fig. 5. This dog remains in this operative position until the front end 70 of a shifting bar 71 is arranged in the path of the tail 69 and causes the coupling dog 65 to be disengaged from the ratchet wheel 64, as shown by dotted lines in Fig. 1, thereby disconnecting the trip disk 62 from the driving shaft 31. The shifting bar 71 is arranged lengthwise and horizontally above the rear part of the feed table or saddle, as shown in Figs. 1, 3, 4, 5, 6 and 7, and is mounted on the main frame of the machine so that the same is capable of horizontal, longitudinal as well as vertical motion relatively to the table or saddle. A forward longitudinal movement of the shifting bar 71 for disengaging the tappet 70 at its front end from the tail 69 of the coupling dog is effected by engagement of the front end of the blank to be stitched with a stop 72 of which one or more may be mounted in a longitudinal row and in spaced relation relatively to each other on the shifting bar 71 in accordance with the number of stitches which are to be applied to the blanks and the relative spacing between adjacent stitches. As shown in Fig. 1, three of such stops are mounted on the shifting bar 71 and

the same are equally spaced relatively to each other. Upon presenting the first booklet, pamphlet or similar blank or article to the feed rolls the latter will advance this blank until the front edge of the same strikes the first stop 72 and moves the latter together with the shifting bar 71 sufficiently forward to move the tappet 70 out of the path of the tail 69. When this occurs the spring 67 immediately throws the dog 65 into engagement with the ratchet wheel 64 so that the trip disk 62 will be compelled to turn with the shaft 31, the timing of the parts being such that when this coupling is effected the cam 63 is immediately in front of the roller 9 of the trip rod 59 so that the first effect of the rotary movement of this trip disk 62 is to depress the trip rod 59 together with the treadle and cause the clutch 13 to be operated for coupling the stitching mechanism with the driving pulley 17 whereby a wire stitcher or staple will be applied to that part of the book or pamphlet which at the time is arranged between the staple forming and clinching mechanism. Immediately after a stitch has been thus applied to the pamphlet the shifting bar 71 is raised so that it will lift the stop 72 which has been engaged by the front edge of the book blank out of the path of the latter and will then lower this shifting bar 71 so as to position the parts for again causing an automatic operation of the stitching mechanism when the book or pamphlet blank has reached the proper position between the staple or stitch forming and clinching mechanism for receiving the next stitch or staple. For this purpose a shifting bar 71 is mounted on the main frame so as to be capable of a longitudinally reciprocating and a vertically oscillating movement by means of a plurality of elbow levers which are pivoted at 73 on a supporting bar 74 forming part of the main frame and each elbow lever having a horizontal arm 75 which is connected by means of a vertical link 76 with the shifting bar 71, and a longitudinally reciprocating lifting bar 77 connected with the lower arms 78 of the elbow levers and provided at its front end with a roller 79 adapted to be engaged by the cam 63 of the trip disk. The shifting bar 71 and the parts associated therewith tend to move automatically by gravity into their initial position, but this movement is aided by means of a spring 80 which connects one of the links 76 with an arm 81 on the adjacent part of the main frame so that this spring tends constantly to move the two bars 71 and 77 forwardly or toward the disks 62, the movement of these parts in this direction being, however, limited by means of a stop 82 mounted on the frame bar 74 and adapted in the present instance to be engaged by the foremost link 76, as shown in Fig. 1.

By means of this construction the cam 63 immediately after depressing the clutch shipper rod 59 for starting the stitching mechanism then engages the roller 79 of the lifting rod 77 and pushes the latter forwardly thereby causing the elbow levers to be turned in the direction for lifting the shifting rod 71 and raising the respective stop 72 which has been engaged by the front edge of the blank out of the path of the latter and thereby permitting this blank to continue in its forward movement, as shown in Fig. 5, under the action of the feed rolls. The cam 63, however, immediately clears the lifting rod 79 after effecting this lifting operation so as to permit the shifting bar 71 to again descend and bring the next following stop 72 into the path of the blank at the summit of the saddle. As soon, therefore, as the blank has been again advanced by the feed rolls and engaged with the next following stop 72 the latter will be again moved forwardly sufficiently to disengage the tappet 70 of the shifting bar out of engagement from the tail 69 of the dog 65, as shown in Fig. 4, when the operation of tripping the main clutch 18, and operating the stitching mechanism, and lifting the respective stop 72 out of the path of the blank is repeated, this automatic operation of the stitching mechanism in this manner recurring as often and at such intervals as may be desired depending on the number of stops 72 which are mounted on the shifting bar 71 and the relative spacing of the same. In order to permit each of the stops 72 after being once lifted to clear the pamphlet which it has arrested to again descend and to be ready for another operation without interfering with the descent of succeeding stops which are about to be engaged by the front edge of the blank, each of the stops 72 is mounted on the shifting bar 71 so that it is capable of engaging yieldingly with the top of the blank which is being stitched. This yielding connection preferably consists of a carrier 83 mounted on the shifting bar 71 and provided with a vertical slot 84 and also provided on its front side with a vertical guide face 85 which is engaged by the vertical rear side 86 of the respective stop 72, two guide lugs 87 projecting forwardly from the upper part of the stop 72 on opposite sides of a carrier 83 and a guide pin 88 passing through the slot 84 and connected at its opposite ends with the lugs 87, as best shown in Figs. 1, 4, 5 and 8. By this means the stop 72 may be lowered into its operative position close to the summit of the saddle so that it will stand in the path of the advancing blank, as shown in Fig. 7, and the same is also capable of yielding by sliding upwardly on its carrier 83 when engaging the top of the blank upon being lowered while over the latter, as shown in Figs.

5 and 6. The lower part of the stop 72 is preferably forked or of bifurcated form, as shown in Figs. 6 and 7 so that it will straddle the saddle and positively arrest the blank which is being fed against the same.

For the purpose of enabling the stops 72 to be adjusted in a different position lengthwise of the shifting bar 71 to suit the desired spacing of the stitches which are to be applied to the pamphlet, each of the carriers 83 is slidably mounted with its upper part on the shifting bar 71 by providing the same with upper and lower hooks 89 and 90 which impress the upper and lower edge of the shifting bar 71 and holding this carrier 83 in position after adjustment by means of a clamping screw 91 arranged on this carrier and adapted to engage with the side of the shifting bar 71, as shown in Figs. 6 and 7.

When the stitched blank reaches the discharge end of the table or saddle 13 the same is positively ejected therefrom by passing between an upper roller 92 which is supported at the lower end of a bar 93 forming part of the main frame and the delivery end of a discharge belt 94 which passes around a delivery roller 95 journaled by means of a shaft 96 on the adjacent part of the main frame. The front turn of the belt 94 passes around a pulley 97 on the shaft 29 from which it receives its motion.

In practice the operator feeds each new unstitched blank close behind the previous blank which is being operated upon by the machine so that in effect a continuous stream of blanks or booklets are being propelled through the machine and stitches applied thereto at predetermined intervals. Under these circumstances the operation of applying stitches to the blank is effected automatically as well as the propulsion of the blank through the machine and no further attention is required on the part of the operator other than to keep supplying the machine with blanks in a continuous stream. If, however, an interruption occurs in the feeding of the blanks then the operation of the stitching mechanism will be automatically arrested when the last stitch has been applied to the blank fed to the machine.

I claim as my invention:—

1. A feeding mechanism for wire stitching machines, comprising a support upon which the article to be stitched is adapted to rest and which is provided with an opening, and feed wheels adapted to engage opposite sides of said article in line with said opening, one of said wheels being provided with a peripheral groove and the other wheel having a peripheral part adapted to deflect said article into said groove.

2. A feeding mechanism for a wire stitching machine, comprising a feed table having an inclined side provided with an opening, a lower conical feed wheel turning about a

horizontal transverse axis and having its upper part projecting upwardly into said opening and provided with a peripheral groove, and an upper cylindrical feed wheel having 5 its axis inclined and parallel with the upper side of said support and arranged above said opening and adapted to deflect a part of said article downwardly into said groove.

3. A feeding mechanism for wire stitching machines, comprising a saddle-shaped support upon which the article to be stitched is adapted to rest and which is provided on opposite sides of its summit with openings, pairs of co-operating feed wheels each pair 10 having a lower conical wheel arranged below one of said openings and provided with a peripheral groove and an upper wheel arranged above the respective opening and adapted to press part of the article to be 15 stitched into said groove, and means for rotating said wheels.

4. A feeding mechanism for wire stitching machines, comprising a saddle-shaped support upon which the article to be stitched 20 is adapted to rest and which is provided on opposite sides of its summit with openings, pairs of co-operating feed wheels each pair having a lower conical wheel arranged below one of said openings and provided with a 25 peripheral groove and an upper wheel arranged above the respective opening and adapted to press part of the article to be stitched into said groove, and means for rotating said upper wheels, comprising an upper 30 driving shaft, driven shafts connected with said upper feed wheels, intermeshing bevel gear wheels connected with said driven shafts, upper and lower intermediate shaft sections which are arranged at an angle relatively 35 to each other, intermeshing gears secured to said driving shaft and said upper intermediate shaft section, a universal joint connecting said intermediate shaft sections, and a bevel gear wheel arranged on the lower intermediate shaft section and meshing 40 with one of said driven bevel gear wheels.

5. A feed mechanism for wire stitching machines, comprising a clutch for connecting with and disconnecting the stitching 45 mechanism from a power source, a feed table, means for propelling the articles to be stitched lengthwise over said table, a stop adapted to be engaged by the article to be stitched, and to be moved thereby, and means for controlling said clutch by motion imparted to said stop by said article, comprising a driving shaft which rotates continuously, a ratchet wheel rotating with said shaft, a disk rotatable and concentric with said shaft, a coupling dog movably mounted on said disk and adapted to be engaged with and disengaged from said ratchet wheel, and a shifting bar carrying said stop and capable of moving lengthwise and also vertically toward and from said table and adapted to be moved into and out of the path of said dog for disengaging the same from said ratchet wheel and permitting the same to engage therewith.

6. A feed mechanism for wire stitching 50 machines, comprising a clutch for connecting with and disconnecting the stitching mechanism from a power source, a feed table, means for propelling the articles to be stitched lengthwise over said table, a stop adapted to be engaged by the article to be stitched, and to be moved thereby, and means for controlling said clutch by motion imparted to said stop by said article, comprising a driving shaft which rotates continuously, a ratchet wheel rotating with said shaft, a disk rotatable and concentric with said shaft, a coupling dog movably mounted on said disk and adapted to be engaged with and disengaged from said ratchet wheel, a shifting bar carrying said stop and capable of moving lengthwise and also vertically toward and from said table and adapted to be moved into and out of the path of said dog for disengaging the same from said ratchet wheel and permitting the same to engage therewith.

7. A feed mechanism for wire stitching 55 machines, comprising a clutch for connecting with and disconnecting the stitching mechanism from a power source, a feed table, means for propelling the articles to be stitched lengthwise over said table, a stop adapted to be engaged by the article to be stitched and to be moved thereby, and means for controlling said clutch by motion imparted to said stop by said article, comprising a driving shaft which rotates continuously, a ratchet wheel rotating with said shaft, a disk rotatable and concentric with said shaft, a coupling dog movably mounted on said disk and adapted to be engaged with and disengaged from said ratchet wheel, a shifting bar carrying said stop and capable of moving lengthwise and also vertically toward and from said table and adapted to be moved into and out of the path of said dog for disengaging the same from said ratchet wheel and permitting the same to engage therewith.

8. A feed mechanism for wire stitching 60 machines, comprising a driving clutch for connecting with and disconnecting the

 stitching mechanism from the source of power, a feed table over which the articles to be stitched are moved, means for controlling said stitching and feeding mechanism including a shifting bar movable lengthwise of the table and also vertically toward and from the same, a stop adapted to be arranged in the path of the articles to be stitched and to be shifted thereby, and means for holding said stop against forward movement on said bar but permitting the same to move vertically thereon.

9. A feed mechanism for wire stitching machines, comprising a driving clutch for connecting with and disconnecting the stitching mechanism from the source of power, a feed table over which the articles to be stitched are moved, means for controlling said stitching and feeding mechanism, including a shifting bar movable lengthwise of the table and also vertically toward and from the same, a stop adapted to be arranged in the path of the articles to be stitched and to be shifted thereby, and means for holding said stop against forward movement on said bar but permitting the same to move vertically thereon, comprising a carrier mounted on said bar and provided with a vertical slot, and having a vertical guide face which is engaged by said stop, and a pair of lugs arranged on opposite sides of said carrier and connected by a pin passing through said slot.

10. A feed mechanism for wire stitching machines, comprising a clutch for connecting with the disconnecting the stitching mechanism from a power source, a feed table, means for propelling the articles to be stitched lengthwise over said table, a stop adapted to be engaged by the article to be stitched and to be moved thereby, and means for controlling said clutch by motion imparted to said stop by said articles, comprising a driving shaft which rotates continuously, a ratchet wheel rotating with said shaft, a disk rotatable and concentric with said shaft, a coupling dog movably mounted on said disk and adapted to be engaged with and disengaged from said ratchet wheel, a shifting bar carrying said stop and capable of moving lengthwise and also vertically toward and from said table and adapted to move into and out of the path of said dog for disengaging the same from said ratchet wheel and permitting the same to engage therewith, elbow levers pivoted on fixed supports, links each connecting one arm of each elbow lever with said shifting bar, a lifting bar connected with the other arms of said elbow levers, a cam arranged on said disk and adapted to engage said lifting bar and move the same in the direction for raising the shifting bar and stop, a spring for moving said shifting bar and associated parts in the opposite direction, and a stop for limiting the movement of said shifting bar and associated parts under the action of said spring.

wheel, a shifting bar carrying said stop and 50 capable of moving lengthwise and also vertically toward and from said table and adapted to move into and out of the path of said dog for disengaging the same from 55 said ratchet wheel and permitting the same to engage therewith, elbow levers each having one arm connected with said shifting bar, a lifting bar connected with the other arms of said elbow levers, and a cam arranged on said disk and adapted to move 60 said lifting bar lengthwise.

11. A feed mechanism for wire stitching machines, comprising a clutch for connecting with and disconnecting the stitching mechanism from a power source, a feed table, means for propelling the articles to be stitched lengthwise over said table, a stop adapted to be engaged by the article to be 65 stitched, and to be moved thereby, and means for controlling said clutch by motion 70 imparted to said stop by said article, comprising a driving shaft which rotates continuously, a ratchet wheel rotating with said shaft, a disk rotatable and concentric with 75 said shaft, a coupling dog movably mounted on said disk and adapted to be engaged with and disengaged from said ratchet wheel, a shifting bar carrying said stop and capable of moving lengthwise and also vertically 80 toward and from said table and adapted to move into and out of the path of said dog for disengaging the same from said ratchet wheel and permitting the same to engage therewith, elbow levers pivoted on fixed supports, links each connecting one arm of each 85 elbow lever with said shifting bar, a lifting bar connected with the other arms of said elbow levers, a cam arranged on said disk and adapted to engage said lifting bar and move the same in the direction for raising the shifting bar and stop, a spring for moving said shifting bar and associated parts in the opposite direction, and a stop for limiting the movement of said shifting bar and associated parts under the action of 90 said spring.

JAMES A. JACOBSEN.
